DESIGN FOR A GARMENT HANGER

Emil Lamar, Berkeley, Calif.

Application March 12, 1940, Serial No. 90,858

Term of patent 14 years

To all whom it may concern:

Be it known that I, Emil Lamar, a citizen of the United States and a resident of Berkeley, in the county of Alameda and State of California, have invented a new, original, and ornamental Design for a Garment Hanger, of which the following is a specification, reference being had to the accompanying drawing, forming part thereof, wherein:

Figures 2 and 3 are top plan and end elevational views, respectively, of the garment hanger.

I claim:

The ornamental design for a garment hanger, substantially as shown.

EMIL LAMAR.
